(57) **CLAIM**

The ornamental design for a waist wrap garment, as shown and described.

DESCRIPTION

FIG. 1 is a perspective view of the waist wrap garment, showing the new design;

FIG. 2 is a front elevational view of the waist wrap garment thereof;

FIG. 3 is a rear elevational view of the waist wrap garment thereof;

FIG. 4 is a left side elevational view of the waist wrap garment thereof;

FIG. 5 is a right side elevational view of the waist wrap garment thereof;

FIG. 6 is a top plan view of the waist wrap garment thereof;

FIG. 7 is a bottom plan view of the waist wrap garment thereof; and,

FIG. 8 is a perspective view of the waist wrap garment, shown in an open, flat configuration.

The broken lines showing a garment in FIG. 1 illustrates environment and forms no part of the claimed design. The broken lines shown on the waist wrap garment illustrate portions of the article and form no part of the claimed design.

1 Claim, 4 Drawing Sheets
